UNITED STATES PATENT OFFICE.

DAVID MCGENNISS, OF AMSTERDAM, NEW YORK.

COMMUTATOR-TRUER.

SPECIFICATION forming part of Letters Patent No. 448,540, dated March 17, 1891.

Application filed June 10, 1890. Serial No. 354,985. (No model.)

To all whom it may concern:

Be it known that I, DAVID MCGENNISS, of Amsterdam, in the county of Montgomery and State of New York, have invented a new and 5 Improved Commutator-Truer, of which the following is a specification, reference being had to the annexed drawings, forming a part thereof, in which—

Figure 1 is a perspective view showing the 10 application of my improved commutator-truer to a dynamo. Fig. 2 is a transverse section taken through one of the supports of the truing-instrument, and Fig. 3 is an inverted plan view of the truing-instrument.

15 Similar letters of reference indicate corresponding parts in all the views.

The object of my invention is to provide a simple and effective device for truing the commutators of dynamo-electric machines and 20 motors after they have been worn by the friction of the brushes and by the action of the current.

My invention consists in a pair of adjustable guides fitted to the brush-holding arm of 25 a commutator, a sliding rod fitted to the guides, and a plate carried by the sliding rod and furnished with an abrading or cutting surface, all as will be hereinafter more fully described.

The commutator-cylinder A, which is mounted 30 on the armature-shaft B and connected with the conductor of the armature C, is constructed and arranged in the usual way.

Upon the journal-box D of the armature-shaft B is adjustably mounted the brush-holding arm E, provided at its extremities with 35 apertures a for receiving the brush-holding rods.

In applying my improvement to a dynamo the brushes and brush-holding rods are 40 moved and in their places are inserted rods F F'. To these rods are fitted the supports G G', consisting of the sleeves b b', fitted to the rods F F' and clamped by set-screws c c' and right-angled arms d d', extending laterally 45 from the sleeves b b' in opposite directions, as shown. The upright portion of the arm d is bored to receive the shank e of the fork H, the said shank being clamped in the arm d by the set-screw f. In the fork H is pivoted a 50 sleeve I upon the ends of the screws g, which

pass through the arms of the said fork. In a plain bore in the upright portion of the arm d' is inserted a screw-threaded rod e', to which is fitted a nut e², bearing upon the top of the arm. The upper end of the rod e' is provided 55 with a fork H', in which is pivoted a sleeve I' on the ends of the screws g'. In the sleeves I I' is inserted a rod J, provided at one end with a handle K for convenience in manipulating the truer. The portion of the rod J 60 passing through the sleeve I' is grooved longitudinally, and in the said sleeve I' is inserted a screw h, which projects into the groove of the rod J and prevents the rod from turning. To the rod J is fitted the apertured 65 ear i of the plate L, and the ear is furnished with a set-screw j, by means of which the plate L may be clamped in any desired position along the length of the rod or at any desired angle with reference to the axis of the commutator-cylinder A. To the undersurface of 70 the plate L is clamped a plate M of abrading material or a plate to which abrasive material has been applied.

In practice I provide emery-blocks of different grades for reducing the surface of the commutator-cylinder to plain cylindrical form. I also provide plates furnished with elastic or semi-elastic pads coated with emery or other abrasive or polishing material for smoothing 80 and finishing the commutator-cylinder after it has been reduced to proper form. The plate L is raised or lowered by turning the nut e² in one direction or the other, and it is moved backward and forward across the commutator-cylinder as the cylinder revolves and is gradually lowered by turning the nut e' until the 85 commutator is made true and provided with a suitable finish for again receiving the commutator-brushes. If the commutator-cylinder is 90 worn conically, the plate L may be inclined at a suitable angle and the commutator-cylinder may be made perfectly round without the necessity of reducing it to a cylindrical form.

Having thus described my invention, I claim as new and desire to secure by Letters Patent—

1. A truing attachment for dynamos, comprising two supports having attaching-rods 100

to enter the brush-rod, apertures at opposite ends of the brush-holding arm, vertical posts mounted in said arms and carrying aligned sleeves, and a rod passed through said sleeves 5 and having an abrader between its ends to engage the surface of said cylinder, substantially as described.

2. A truing attachment for dynamos, comprising supports adapted for connection with 10 the opposite ends of the brush-carrying arm, vertically-adjustable posts carried by said supports, vertically-rocking aligned sleeves mounted on said posts, and a rod extending through both sleeves and provided with an 15 abrading device between its ends, substantially as described.

3. In a commutator-truer, the combination of a support adapted for attachment to the brush-supporting arm, a rod movable length- 20 wise in the support, and an adjustable abrad-

ing-plate carried by the rod, substantially as specified.

4. In a commutator-truer, the combination of the supports G G', the adjustable forked rod e, the threaded forked rod e', the nut e², 25 fitted to the rod e', the sleeves I I', the sliding rod J, and the plate L, provided with the apertured ear i and the set-screw j, substantially as specified.

5. The combination, with the brush-holding 30 arm E and the commutator-cylinder A of a dynamo, of an abrading-plate L, and supports fitted to the arm E at opposite sides of said cylinder and adapted to hold the plate in the position of use, substantially as specified.

DAVID McGENNISS.
